SEALING MECHANISM

Henry T. Scott, Toledo, Ohio, assignor to The
American Paper Bottle Company, Toledo, Ohio,
a corporation of Ohio

Application August 24, 1934, Serial No. 741,330

9 Claims. (Cl. 226—56)

The present invention relates to sealing mechanisms and particularly to mechanisms for imparting final sealing pressure to the folded, paraffin impregnated closure end portion of a paper container of the type used for the packaging of liquids, whereby the end of such container is effectively sealed against the escape of liquid which has been previously introduced.

In the pending application of John R. Van Wormer, Serial Number 277,414, filed May 14, 1928, is disclosed a method of and apparatus for forming, liquid proofing, charging and sealing paper containers. In accordance with the process set forth in that application a paper blank is first formed into a container, sealed at one end and square or substantially square in cross section, the opposite end having a foldable portion adapted to form the closure thereof. The container is then coated with paraffin or some other suitable liquid proofing substance. After the paraffin has hardened the container is charged with a liquid, for instance, milk, and after the charging operation has been completed the upper end portion of the container, which is divided by score lines into panels, is folded along the score lines in such manner that a transversely extending central upstanding rib results, this rib comprising several parallel plies of paraffin impregnated paper. It is then necessary to compress the several plies of this rib tightly together in order to effectively seal the end of the container against leakage, the paraffin coating of the several plies which comprise the rib being preferably rendered plastic or semi-plastic by heating just prior or during the pressing operation so that the paraffin will flow into all the interstices of the rib to effectively close any channels, however minute, through which liquid might subsequently escape.

In order to form a thoroughly leak proof seal a heavy pressure should be applied to the rib. Furthermore, the pressure applying mechanism should be of such nature as to be able to perform its functions quickly, inasmuch as the entire package forming, charging, and sealing operations are preferably performed by means of an automatic machine designed to operate at relatively high speed.

In accordance with the present invention a sealing mechanism is provided by means of which such a sealing operation as has just been described may be performed with great rapidity while, at the same time, the necessary heavy pressure is applied. The novel sealing mechanism is of great ruggedness and simplicity, occupies but

small space and may readily and conveniently be attached so as to form an element of the complete machine. Speed of operation is promoted, while at the same time the ability of the machine to exert the necessary heavy pressure is maintained, by providing means for first producing a relatively rapid closing movement of the jaws, or until the jaws are in substantial contact with the container rib, and a second means which then becomes active to produce the further final closing movement of the jaws and the necessary heavy pressure. This second means produces a closing movement of the jaws which is much slower than that produced by the first jaw closing means but is so designed as to be able to produce a much heavier thrust of the jaws against the work. The machine therefore includes means for producing rapid closing movement of the jaws up until the time that heavy pressures are required and additional means for thereafter producing the heavy pressures required, this last means being slower in motion but able to develop greater forces. Naturally, in adapting the principles of the invention to the performance of various types of work the design and arrangement of its component elements may be considerably varied. That form of the invention which is illustrated in the accompanying drawings, therefore, is set forth by way of example only.

In the drawings:

Fig. 1 is a side elevation of portion of an automatic paper bottle machine, the novel sealing mechanism being shown;

Fig. 2 is a section on line 2—2 of Fig. 1;

Fig. 3 is a section on line 3—3 of Fig. 2;

Fig. 4 is a perspective view of portion of the pressure producing mechanism;

Fig. 5 is a section on line 5—5 of Fig. 3;

Fig. 6 is a side elevation of portion of the mechanism for producing the initial rapid closing movement of the jaws; and

Fig. 7 is a partial section through portion of the mechanism, showing certain of the elements thereof in modified form.

While the working members or elements of the apparatus may be supported in any suitable manner, the frame illustrated in Figs. 1, 2 and 3 is suitable. This frame includes a horizontally disposed member 10 which, when attached to an automatic paper bottle making machine, extends transversely of the machine and has its ends supported respectively, upon the upright side members thereof, such as the members 11 and 12 respectively. Two longitudinally extend-

ing conveyor chain trackways are indicated at 13 and 14 and a conveyor chain is indicated generally at 15, the chain being provided with rollers 16 which run in mutually facing grooves formed in the inner surfaces of the parallel tracks 13 and 14 respectively. Conveyor chain 15 is provided with upwardly projecting elements 17, only one of which is shown, for moving paper containers, one of which is diagrammatically indicated at 18, longitudinally of the machine and transversely to the frame member 10, the upper central rib 18' of the container being guided by a U-shaped guide member 20 to a position intermediate the relatively movable jaws 21 and 22 of the sealing mechanism, whereupon the forward movement of the conveyor chain is temporarily halted while the sealing operation is performed.

To effect the compression of the rib the relatively movable jaws 21 and 22 are caused to approach each other, first rapidly during the time that no substantial pressure of the rib is taking place and thereafter more slowly, while heavy pressure is exerted. After the seal has been effected the jaws are moved apart, the initial opening movement of the jaws being relatively slow and the final opening movement of the jaws being relatively fast. After the jaws have disengaged the rib the conveyor chain 15 will then continue its movement, removing the sealed container from between the jaws and introducing the rib of an unsealed container.

As it is desired to maintain the jaws at a relatively high temperature during the sealing operation in order that the paraffin upon the rib of the carton may be rendered plastic and easily flowable, a heating means is provided. This heating means may be of any desired nature but I prefer to utilize steam as the heating fluid and hence provide a heating chamber 28 in close proximity to the jaws and conduits for introducing live steam to this chamber and exhausting steam and water of condensation therefrom, these conduits being indicated at 26 and 28 respectively. The heat delivered by the steam is transferred by conduction to the jaws 21 and 22, the frame being fabricated of metal.

Both of the jaws 21 and 22 may be movable but I prefer to mount one of them, in this case, jaw 21, rigidly upon the frame and to effect the relative movement of the jaws by providing means for the movement of jaw 22 alone. Jaw 21 is illustrated only in cross section in the drawings but it will be understood that this jaw is of such length as to present an elongated active bearing face to the container rib, and jaw 22 is of similar dimensions. Jaw 21 may be attached to the frame by any suitable means but I preferably provide it with a dovetailed portion 21' which fits within a dovetail slot formed in the frame member 10' so as to be longitudinally insertable into this slot, a set screw 26 being provided to prevent displacement.

Jaw 22 is mounted upon the end of a bolt 27 which is axially movable but non-rotatable, having a squared portion slidably mounted within a similarly formed bearing 28 which forms a portion of the frame. That portion of the bolt 27 which lies immediately to the right of the bearing 28 is threaded, as shown in Fig. 3, and rotatably mounted upon this threaded portion is an externally toothed and internally threaded nut 30, the teeth of this nut meshing with the teeth of a segment 31 fixed upon a shaft 32 suitably supported in bearings formed in the frame

10, the axis of rock shaft 32 being parallel to the axis of bolt 27. An axially extending sleeve-like portion 33 of nut 30 projects into a recess 34 formed in a sliding block 35, movable in a vertical plane which includes the axis of the bolt 27, sleeve-like portion 33 having at its end an annular flange or collar 36 located entirely within recess 34. As can be more clearly seen from an inspection of Fig. 5, sliding block 35 is provided with vertically extending parallel flanges 37 the distance between which, measured horizontally, is less than the diameter of the flange 36 of nut extension 33, so that the nut and sliding block are interconnected at all times.

In rear of flange 36 and encircling bolt 27 is a thrust bearing 38, one race of this bearing resting against the inner wall of recess 34 and the other against the end of nut 30, both races encircling the bolt and the bearing being of such thickness that substantial movement of nut 30 relative to block 35 in a direction parallel to the axis of bolt 27 is prevented while at the same time vertical movement of the sliding block 35 relatively to the bolt and nut may freely occur.

Sliding block 35 in reality comprises a wedging means for producing, as it moves vertically upwardly and downwardly, axial movement of bolt 27. It may be designated a wedging means by reason of the fact that it is wedge-shaped in a vertical figure taken on the axis of bolt 27, the face of the block remote from the nut being inclined, as shown more clearly in Fig. 6, and having sliding engagement with the correspondingly inclined face of a stationary guide block 40 suitably supported upon the frame. Preferably the sliding block or wedging means is provided with an under cut recess and the guide block 40 with a flanged rib which closely fits within such recess. With this construction, block 35 is positively connected to guide block 40 at all times although readily slideable relatively thereto in a vertical plane. By reason of the interconnection of the wedging block 35 and nut 30, which nut is in turn threaded upon bolt 27, it is clear that an upward movement of sliding block 35 will effect separation of the jaws 21 and 22 and that a downward movement of this block will cause jaw 22 to approach jaw 21. By reason of the fact also that the inter-engaging faces of the sliding block 35 and guide block 40 are disposed at substantial angles to the vertical, movements of the block 35 produce relatively rapid movements of jaw 22 toward or away from jaw 21, depending upon the direction of movement of block 35.

In order to produce the vertical movements of block 35 and hence rapid movements of jaw 22, a camming mechanism is provided for positively raising and lowering this block. This camming mechanism includes a rocker arm 45 pivoted at approximately its mid point upon an extension 46 of the frame, this rocker arm having in turn pivoted to its upper and lower ends respectively, the upper and lower camming members 47 and 48, which members might likewise be designated axially movable slides since each is slidably supported in a suitable bearing formed in the frame, for axial movement only. In order to prevent binding, the ends of the rocker 45 are connected to the ends of the slides 47 and 48 respectively by pin and slot connections.

The free ends of the upper and lower camming members 47 and 48 are inclined or bevelled, the bevelled face of the inner end of the upper camming member 47 being adapted to slidably engage

a correspondingly bevelled surface 49 formed on the upper corner of the sliding block 35 and the bevelled end surface of the lower camming member 48 being adapted to engage a correspondingly 5 inclined surface 50 formed on the extension 51 of sliding block 35. As will be readily observed, upon inspection of the drawings, the upper and lower camming members 47 and 48 will cooperate, when rocker arm 45 is moved, in raising and lowering the sliding block 35 and in positively moving the same from its upper position to its lower position, or vice versa, depending upon the direction of rotation of the rocker. The part 51 of sliding block 35 is formed separately from the main position of the block and is attached thereto, as by means of screws 52, for reasons of convenience of assembly and manufacture. Intermittent motion is imparted to rocker 45 by means of a rotary cam 54 fixed upon a rotatable shaft 55, a roller 56 20 secured to the lower end of rocker 45 lying within the cam groove 57.

Intermittent motion is imparted to segment 31 through shaft 32, arm 58 fixed on the end of this shaft, link 59 pivoted to the end of arm 58, 25 slide 60, roller 61 carried by the slide and cam member 62 which may likewise be fixed upon shaft 55. Slide 60 is guided, so as to move in a definite fixed horizontal path, by means of a guide 63 secured to a frame member and the cam slot 30 64 of cam 62 is so formed as to produce swinging movement of segment 31, through the interconnecting mechanism just described, at the desired times.

The cam slots of the two cams 54 and 62 are 35 so formed in relationship to each other that in effecting a closing movement of jaw 22 relatively to jaw 21, the wedging means or sliding block 35 is first lowered by the cooperation of the upper and lower camming members 47 and 48, block 35 40 moving toward the left (Fig. 3) during its lowering movement and hence also thrusting bolt 27 rapidly toward the left, the teeth of nut 30 simply sliding relatively to the teeth of segment 31. Immediately upon the wedging means 35 reaching 45 its lowermost position, the segment 31 becomes active and causes rotation of nut 30 on bolt 27. This rotation of nut 30 is in such direction as to cause further forward movement of the bolt, the nut itself being securely anchored to block 35 and 50 which block is at the same time also definitely maintained in position by the camming mechanism described.

As will be seen from an inspection of Figures 2 and 4 the upper camming member 47 has a 55 cylindrical central portion which slidably fits within a cylindrical aperture or bearing formed in the frame, and a forwardly extending portion with flat parallel upper and lower faces. When member 47 has been fully advanced and block 60 35 fully depressed the forward end of this member is interposed between the flat upper surface of the block and a parallel surface of the frame with the flat lower surface of member 47 in close 65 contact with the block and the flat upper surface of this member in close contact with a parallel surface of the frame. The block is thus positively locked in its lowermost position until member 47 is withdrawn.

The result of the rotation of nut 30 is therefore to give the bolt 27 and jaw 22 a relatively 70 slow advancing or closing movement, which is the final closing movement of the sealing apparatus and imparts a heavy pressure upon the container rib. This pressure may be very heavy by 75 reason of the mechanical advantage derived from

the use of the bolt 27 and nut 30. At the conclusion of this further advancing movement of the bolt due to rotation of nut 30 the container pressing operation is completed and it only remains to withdraw jaw 22. Retraction of the jaw is effected first by movement of segment 31 and rotation of nut 30 in the opposite direction, thus relieving the heavy pressure, and thereafter by upward movement of the wedging block 35, whereupon the sealed container may be removed 10 and the conveyor caused to remove it and to insert the rib of an unsealed container between the pressure jaws.

The jaw closing mechanism may therefore be said to comprise two separate means for connecting the jaw to a single source of power, i. e. the shaft 55, one such means producing a rapid initial closing movement of the jaws and the second a considerably slower but more powerful closing movement of the jaws. If desired, of course, these two closing means may be actuated from separably driven shafts but for the purposes of simplicity and convenience it is preferred to actuate them from a single power source.

In the form of the invention shown in Fig. 7 the lower camming member is omitted and a spring 70 substituted therefor. The lower end of this spring is mounted upon the upper end of an adjusting screw 71 having threaded relation with a stirrup-like cross member 72 secured to the frame 10. The upper end of the spring bears against the bottom of sliding block 35, the shape of which has been slightly modified, as shown, and the ends of the spring are so connected to the adjusting screw and sliding block that the spring may rock slightly as the block moves vertically and horizontally. Naturally, other features of the invention may be slightly modified in adapting the same to the 40 performance of different tasks throughout the mechanical arts.

Having thus described the invention, what is claimed as new and desired to be secured by Letters Patent is:

1. Apparatus for sealing containers comprising, relatively movable work engaging jaws, a movable member upon which one of said jaws is supported, a source of power, and separate means operatively connecting the power source 50 and member whereby the member may be given a preliminary relatively rapid closing movement by one such means, and thereafter a final relatively slow closing movement by another means.

2. Apparatus for sealing containers comprising, a frame, a jaw carrying threaded bolt mounted in the frame for longitudinal movement, an externally toothed nut having threaded engagement with said bolt, rotation of said nut effecting axial movement of the bolt, a wedging 60 means in axial alignment with the bolt, also for imparting axial motion thereto, and means for first operating the wedging means to produce a rapid closing motion of the bolt and thereafter operating the nut to produce a slower closing 65 motion of the bolt.

3. The combination set forth in claim 2 in which a thrust bearing is interposed between the end of the bolt and the wedging means.

4. The combination set forth in claim 2 in 70 which the bolt end is slidably connected to a wedge block which is movable transversely of the bolt.

5. The combination set forth in claim 2 in 75 which the bolt end is operatively connected to a

wedge block slidable transversely thereof and in which means is provided for positively sliding said wedge block in opposite directions.

6. The combination set forth in claim 2 in which the bolt end is operatively connected to a wedge block slidable transversely thereof, and in which sliding movement of the block is produced by spaced alternately acting camming members.

10 7. Apparatus for sealing containers comprising a frame, relatively movable work engaging jaws, and means for effecting relative movements of said jaws, said means including a member operatively connected to a jaw, a device for acting on said member to produce a preliminary relatively rapid movement thereof, and a second device formed separately from, and movable relatively to, said first device, for acting on said member to effect a final relatively slow jaw closing movement thereof.

15 8. Apparatus for sealing containers comprising a frame, relatively movable work engaging jaws,

and means for effecting relative movements of said jaws, said means including a member operatively connected to a jaw, a wedge device for acting on said member to produce a preliminary relatively rapid movement thereof, and a device 5 having a threaded element operatively connected to said member and revoluble about an axis, for effecting a final relatively slow jaw closing movement thereof.

9. Apparatus for sealing containers comprising 10 a frame, relatively movable work engaging jaws, and means for effecting relative movements of said jaws, said means including a member operatively connected to a jaw and having a cylindrical threaded portion, a wedge device for 15 acting on said member to produce a preliminary relatively rapid movement thereof, and a device having a threaded element rotatably mounted on the threaded portion of said member, and revoluble about the axis of said member, for effecting a final relatively slow jaw closing movement thereof.

HENRY T. SCOTT.
